UNITED STATES PATENT OFFICE

JOSEPH AUGUSTE RHO, OF MONTREAL, QUEBEC, CANADA, ASSIGNOR TO J. EMILIE
BEAUCHAMP, OF MONTREAL, QUEBEC, CANADA.

FOLDING CHAIR.

1,228,967.

Specification of Letters Patent.

Patented June 5, 1917.

Application filed April 1, 1916. Serial No. 88,261.

To all whom it may concern:

Be it known that I, JOSEPH AUGUSTE RHO, a subject of the King of Great Britain, and residing at 204 Berri street, in the city 5 of Montreal, in the Province of Quebec, in the Dominion of Canada, have invented certain new and useful Improvements in Folding Chairs; and I do hereby declare that the following is a full, clear, and exact description 10 of the same.

The invention relates to a "folding chair" and the object of the invention is to provide a comfortable chair that may be adapted to rock or can be placed in any wanted position. 15

The invention will be described in the accompanying specification and drawing, in which Figure 1 is a side elevation of the chair, showing it in its utmost extended position with the foot-rest adapted thereto. 20

Fig. 2 is a side elevation of the chair in its upright position.

Like numerals of reference indicate corresponding parts in each figure.

25 In the drawings, 1 and 2 are the uprights pivotally secured to the rockers 3, and 4 is the arm-rest or cross-bar secured at one end to the uprights 1 and at the other end to the uprights 2.

30 5, 6, 7 and 8 are cross braces securing together the uprights 1 and 2 to the corresponding uprights on the other side, and the rockers 3 to the corresponding rocker.

35 9 are dents or notches provided on the upper side of the rockers 3, and 10 is a bar pivotally secured to the upright 1 and arm-rest 4, having the brace or cross-bar 11 securing both ends of the bar and adapted to engage the notches 9 on the rockers 3.

40 The rockers 3 are each provided with a downwardly projecting lug at its rear end, forming a flat contact surface which, when the chair is in its utmost extended position, will prevent the chair from rocking, (this 45 being due to the fact that there will be two contacting points), and which, at the same time, will prevent it from overturning.

12 is a foot-rest formed of two longitudi-

nal members 13 and cross-members 14, and 50 15 are legs or posts pivotally secured to one end of said longitudinal members the other ends of said longitudinal members 13 being provided with hooks or notches 16.

17 is a piece of canvas or any suitable material secured at one end to the brace 5 in 55 the uppermost part of the uprights 2 and at the other end to the cross-bar or brace 6, which is secured intermediate in the uprights 1.

18 is another piece of canvas or any suitable material secured to the cross-bars 14 60 between the longitudinal members 13.

In Fig. 2, the foot-rest has been moved into inoperative position, and this is done by reversing the position from the foot-rest 65 as shown in Fig. 1 to the position shown in dotted lines in Fig. 2, and by hooking the projecting members 16 to the intermediate bar 6.

In Fig. 1 is shown a head-rest 19 detachably supported on the cross bar 5 by means of the hook-shaped ends 20. 70

The invention herein described is of simple construction, compact when folded, light and particularly strong. 75

This chair is particularly suitable for verandas, sanatoriums and hospitals, as it can be placed in any wanted position and is most comfortable.

What I claim is:

A folding chair comprising two forward and two rear upright members, said forward members being suitably secured by a cross bar intermediate of their height, and said rear upright members being secured by 85 a cross bar at their upper end; rockers suitably secured by cross bars and adapted to be pivotally connected to the lower ends of said upright members, said rockers being provided with notches on the top of their rear portion; arm rests pivotally secured to said upright members, said arm rests terminating at said rear uprights; a seat made of flexible material between said uprights, secured to the cross bar in the upper end of 90 95 said rear upright members at one end, and

at the other end to the cross bar secured intermediate of the length of the forward upright members; shifting supports pivotally secured to the upper end of said forward uprights at one end and engaging the notches provided on the rockers, substantially as described.

Copies of this patent may be obtained for five cents each, by addressing the "Commissioner of Patents, Washington, D. C."

Signed at Montreal, Quebec, Canada, this 29th day of February 1916.

JOSEPH AUGUSTE RHO.
